William T. Beatty
By Cheever & Cox
Attns.

UNITED STATES PATENT OFFICE.

WILLIAM T. BEATTY, OF FLOSSMOOR, ILLINOIS.

COMBINATION BLADE EXTENSION AND WING FOR ROAD MACHINES.

Application filed July 28, 1922. Serial No. 578,086.

To all whom it may concern:

Be it known that I, WILLIAM T. BEATTY, a citizen of the United States, residing at Flossmoor, in the county of Cook and State 5 of Illinois, have invented a certain new and useful Improvement in Combination Blade Extensions and Wings for Road Machines, of which the following is a specification.

This invention relates to road working 10 machines employing a transverse blade of substantial length, sharpened not only at its bottom for scraping the road surface but at its ends for cutting banks or piles of material at the side of the road.

15 The main object of the invention is to provide a supplemental upright board or plate which, while sufficiently permanently attached to the blade so that it cannot be left at the home of the machine or by the roadside, is adjustable to three different positions: (a) that in which it is a forwardly extending "wing" rendering the blade a conventional form of scraper; (b) that in which it is an "extension" in substantial 25 alignment with the blade, thereby lengthening it for any suitable purpose; and (c) that in which it is supported above and behind the blade out of the way of the blade in all of its working movements.

30 The invention consists in mechanism capable of attaining the foregoing and other objects and particularly in a hinge device adjustable in many ways hereafter referred to, carrying the board or plate to attain the desired objects, the same being economically constructable, satisfactory in use, and not readily liable to get out of order.

The invention further consists in many features and details of construction which 40 will be hereafter more fully set forth in the specification and claims.

Referring to the drawings in which like numerals designate the same parts throughout the several views:

45 Figure 1 is a side elevation of a conventional form of road machine, having the cutting blade equipped with mechanism of this invention in its preferred form.

Figure 2 is a plan view of the machine of 50 Figure 1, showing the parts in the position in which the blade and supplemental board or plates form a conventional form of scraper.

Figure 2^a is a greatly reduced changed 55 position view of Figure 2, showing the parts

in the position in which the blade is lengthened by the plates.

Figure 3 is a plan view of the blade carrying part, proper, of the road machine, with the blade at an angle thereto, one end plate 60 being in alignment therewith to lengthen the blade, the other plate being folded back of the blade in idle carrying position.

Figure 4 is an enlarged detail plan view of the plate supporting hinge mechanism 65 taken on the line 4-4 of Figure 1.

Figure 5 is a changed position view of the hinge mechanism of Figure 4.

Figure 6 is a rear view of the blade with the parts positioned as shown in Figure 3. 70

Figure 7 is an enlarged plan view of the plate carrying hinge mechanism when the parts are in the position of Figures 1 and 2.

Figure 8 is a side view of the hinge mechanism when in the position of Figure 7. 75

Figure 9 is a perspective view taken from the side and rear of the blade when the plate is in forwardly extending "wing" position.

Figure 10 is a disassembled view of the plate and hinge supporting parts separated 80 one from the other.

Figure 11 is a plan and Figure 12 is a side view of a modified construction.

The mechanism of this invention is applicable to the end of any conventional form 85 of road machine blade. For the purposes of illustration, the device is shown applied to opposite ends of the blade 10, extending transversely of the main frame of a conventional form of road machine 12 sustained 90

by wheels 14 and 16. The blade is shown conventionally mounted on blade carrying frame 18, pivoted to the front axle at 20 so as to be controllable in conventional manner by manipulating the hand wheels 22. 95 The blade is directly supported from the frame 24 which is conventionally rotatable under the control of operating wheel 26 and gear mechanism 27 between the angular positions of Figures 2 and 3. 100

The blade 10 may be of any suitable cross section. In the particular case here illustrated, it is curved as shown, for instance, in dotted lines Figure 8, and is provided at its bottom with a cutting edge 28 engageable with the road surface and with sharpened vertical end edges 30 adapted for severing earth material from banks or piles at the side of the road adjacent to the path of travel of the road machine. The problem 110

solved by this invention is to apply, in proximity to these vertical cutting edges 30, plate or board members 32 adapted to be selectively moved to the position of Figure 2 in which they, acting as conventional "wings" convert the blade into a scraper; to the position of Figure 2' in which they act as conventional "extensions" of the blade and therefore enable the user to tilt the blade 10 to the angular position of Figure 3 with reference to the main frame 12 of the machine and still scrape full road width; and, finally, to the position as shown at the left hand portions of Figures 3 and 6 in which 15 they are simply carried by the machine, specifically by the blade, out of its way.

In order to secure this desired result, these plates are carried on supporting hinge mechanisms secured to opposite ends of the blade, 20 the hinge mechanisms being identical except that one is a right hand and the other is a left. These hinge mechanisms or pivotal mounting devices for the plates each include two parallel hinge pivot shafts or bolts 34 and 36 spaced apart a substantial distance by a compound leaf or lever 40-42, adjustable vertically with reference to each other by pin 44 and slot 46 connections, clearly appearing in Figures 9 and 10. As one 30 plate 40 of this leaf includes one hinge pivot 34 and the other leaf member 42 includes the other hinge pivot 36, it is obvious that when pivot member 36 is rigidly positioned on the blade, as it is by means of the 35 stationary hinge leaf 48 secured in place by bolts or screws 50, the hinge pivot 34 can be adjusted vertically with reference to the blade through the conventional operation of the pin and slot connecting device 44-46. 40 The length of the common leaf 40-42 between hinge pivots is such that when the parts are in the position of Figure 9, the plate 32 attached to hinge pivot 34 by means of its independent hinge leaf 52 will just 45 fit around the end of the blade and act as a "wing" in conventional manner, and that when the parts are swung into the position shown in the left hand half of Figure 6, the plate 32 is carried toward the center of the 50 machine a very substantial distance away from the end cutting edge 30 of the blade, thereby leaving that end cutting edge free to act in bank cutting or the like as may be required of the general machine. 55 Plate 32 is vertically adjustable angularly with reference to the hinge wing 52 through the agency of circular slots 54 and pin or bolt connections 56 through them to enable the operator to selectively position the adjacent plate 32 in the full line position at the right hand half of Figure 6 in which the outer end of the plate "extension" is slightly off from the ground 58, thereby 60 lightening the working load upon the "extension" or in the dotted line position in

which the lower edge of the plate contacts the ground.

As the plate when operating either as a "wing" or an "extension" of blade 10 has to carry considerably working strain, it is necessary that it be strongly supported in either position. In the preferred form of construction now under discussion, this is accomplished by providing the hinge leaves 40 and 52 with horizontally disposed overlapping quadrant flanges 60 and 62, suitably perforated with selectively interfitting holes 64 and 66 so that when the parts are properly assembled, the locking bolts 68 can be put in place to rigidly fasten the hinge parts in the position of Figures 2 or 3 as the case may be. In the alternative construction of Figures 11 and 12, flanges 60 and 62 and the attaching bolt devices are entirely omitted and the plates are sustained in working position by the chain 70 of adjustable length as shown in Figure 12. The full lines of Figure 11 show the position of the chain when the plate is in "wing" position, while the dotted lines show the plate and chain when in "extension" position.

In order to detachably secure the hinge mechanism or pivotal mounting device for the plate to the end of the blade 10, when the plate is in "wing" or "extension" positions, a pivoted locking dog 72 is journaled on the hinge bolt 34 to rock through a suitable notch 74 in hinge leaf 52 and catch over the end cutting edge 30 of the blade 10. This dog 72 is detachably secured in locked position by means of a removable pin 76 inserted through a perforation 78, provided for it in the dog. The end of the dog 72 which carries this perforation 78 is, after removal of the pin 76, rockable through a notch 80 in the hinge leaf 40 to release the hook end 82 of the dog from the blade edge 30. By the construction just described, the intermediate or common leaf 40-42 may be rigidly locked in the position of Figure 9 to the back of the blade 10 and kept there while the plate 32 is swung between "wing" and "extension" position as desired. On the other hand, when the pin 76 is removed and the latch dog 72 released the operator can freely move the hinge parts from the position of Figure 9 to that of the left hand part of Figure 6 in which the plate is carried back of the blade and clear of its in-cutting edge. When the parts are moved to this position, it is desirable to adjust the pin and slot connections 44-46, as shown in Figure 6, to elevate the plate entirely clear of the ground, readjusting these parts to the position of Figure 9 when the plate is returned to either "wing" or "extension" working position.

In Figure 8, the hinge bolt 34 is shown in an exaggerated way at a very marked angle 130

to the vertical axis of the blade 10 and the hinged end of plate 32. In practice, the hinge pivots are placed at an angle less than that shown so that the plate will, when 5 swung from "wing" to "extension" working position, be normally in the full line position of the right hand end of Figure 6 with its outer end slightly elevated from the ground 58.

10 In the general operation of the device, if the road machine is to use its blade 10 for normal road cutting operations, with the blade at right angles to the axis of the machine frame as shown in Figures 1 and 2, 15 the plate 32 will be normally assembled out of use as shown in the left hand half of Figure 6. If the operator desires to shift the blade to the angular position of Figure 3 and yet wants to work full width of road, 20 he will adjust the bolts 44 and 68 and the latch 72 to assemble the parts as shown in the right hand half of Figure 6. If the operator desires to use the blade as a scraper for delivering loose dirt in holes along the 25 surface of the road, he will remove the bolts 68 and adjust the plates to the "wing" position of Figure 2 and then replace the bolt 68.

By the use of the device described, the 30 road machine driver always has the working plates 32 with him when he wants to use them and he can at will use them as "wings" or "extensions".

What I claim is:

35 1. In mechanism of the class described, a cutting blade, a dirt controlling plate, and a pivotal mounting device attaching the plate at the end of the blade so constructed and arranged that the plate may be selectively located at 90° to the front of the blade, in approximate alignment with the blade, or at 180° from that position and on the back of the blade.

40 2. In mechanism of the class described, a cutting blade, a dirt controlling plate, a pivotal mounting device attaching the plate at the end of the blade so constructed and arranged that the plate may be selectively located at 90° to the front of the blade, in approximate alignment with the blade, or at 180° from that position and on the back of the blade, and selectively lockable means rigidly confining the plate and blade in each of said first two mentioned positions.

45 3. In mechanism of the class described, a cutting blade, a dirt controlling plate, a pivotal mounting device attaching the plate at the end of the blade so constructed and arranged that the plate may be selectively located at 90° to the front of the blade, in approximate alignment with the blade, or at 180° from that position and on the back of the blade, and means selectively positioning the entire pivotal mounting across the blade 50 lengthwise of its cutting end.

4. In mechanism of the class described, a cutting blade, a dirt controlling plate, a pivotal mounting device attaching the plate at the end of the blade so constructed and arranged that the plate may be selectively located at 90° to the front of the blade, in approximate alignment with the blade, or at 180° from that position and on the back of the blade, selectively lockable means rigidly confining the plate and blade in each of said first two mentioned positions, and means selectively positioning the entire pivotal mounting across the blade lengthwise of its cutting end. 70

5. In mechanism of the class described, a cutting blade, a dirt controlling plate, a pivotal mounting device attaching the plate at the end of the blade so constructed and arranged that the plate may be selectively located at 90° to the front of the blade, in approximate alignment with the blade, or at 180° from that position and on the back of the blade, and means selectively positioning the plate in the arc of a circle about a point on the pivotal mounting device. 80

6. In mechanism of the class described, a cutting blade, a dirt controlling plate, a pivotal mounting device attaching the plate at the end of the blade so constructed and arranged that the plate may be selectively located at 90° to the front of the blade, in approximate alignment with the blade, or at 180° from that position and on the back of the blade, selectively lockable means rigidly confining the plate and blade in each of said first two mentioned positions, and means selectively positioning the plate in the arc of a circle about a point on the pivotal mounting device. 90

7. In mechanism of the class described, a cutting blade, a dirt controlling plate, a pivotal mounting device attaching the plate at the end of the blade so constructed and arranged that the plate may be selectively located at 90° to the front of the blade, in approximate alignment with the blade, or at 180° from that position and on the back of the blade, means selectively positioning the entire pivotal mounting across the blade lengthwise of its cutting end, and means selectively positioning the plate in the arc of a circle about a point on the pivotal mounting device. 105

8. In mechanism of the class described, a cutting blade, a dirt controlling plate, a pivotal mounting device attaching the plate at the end of the blade so constructed and arranged that the plate may be selectively located at 90° to the front of the blade, in approximate alignment with the blade, or at 180° from that position and on the back of the blade, selectively lockable means rigidly confining the plate and blade in each of said first two mentioned positions, means selectively positioning the entire pivotal 110

115

120

125

130

mounting across the blade lengthwise of its cutting end, and means selectively positioning the plate in the arc of a circle about a point on the pivotal mounting device.

5 9. In mechanism of the class described, a cutting blade, a dirt controlling plate, and a pivotal mounting device comprising two parallel hinge pivots, each carrying an independent hinge leaf and a common leaf between them, attaching the plate at the end of the blade so constructed and arranged that the plate may be selectively located at 90° to the front of the blade, in approximate alignment with the blade, or 10 at 180° from that position and on the back of the blade.

10 10. In mechanism of the class described, a cutting blade, a dirt controlling plate, a pivotal mounting device comprising two parallel hinge pivots, each carrying an independent hinge leaf and a common leaf between them, attaching the plate at the end of the blade, so constructed and arranged that the plate may be selectively located at 20 90° to the front of the blade, in approximate alignment with the blade, or at 180° from that position and on the back of the blade, and selectively lockable means rigidly confining the plate and blade in each of said 25 first two mentioned positions.

30 11. In mechanism of the class described, a cutting blade, a dirt controlling plate, a pivotal mounting device comprising two parallel hinge pivots each carrying an independent hinge leaf and a common leaf between them, attaching the plate at the end of the blade so constructed and arranged that the plate may be selectively located at 35 90° to the front of the blade, in approximate alignment with the blade, or at 180° from that position and on the back of the blade, and means selectively positioning the entire pivotal mounting across the blade lengthwise of its cutting end.

40 12. In mechanism of the class described, a cutting blade, a dirt controlling plate, a pivotal mounting device comprising two parallel hinge pivots each carrying an independent hinge leaf and a common leaf between them, attaching the plate at the end of the blade, so constructed and arranged that the plate may be selectively located at 45 90° to the front of the blade, in approximate alignment with the blade, or at 180° from that position and on the back of the blade, selectively lockable means rigidly confining the plate and blade in each of said first two mentioned positions, and means selectively positioning the entire pivotal mounting across 50 the blade lengthwise of its cutting end.

55 13. In mechanism of the class described, a cutting blade, a dirt controlling plate, a pivotal mounting device comprising two parallel hinge pivots each carrying an independent hinge leaf and a common leaf be-

tween them, attaching the plate at the end of the blade, so constructed and arranged that the plate may be selectively located at 90° to the front of the blade, in approximate alignment with the blade, or at 180° from that position and on the back of the blade, and means selectively positioning the plate in the arc of a circle about a point on the pivotal mounting device.

60 14. In mechanism of the class described, a cutting blade, a dirt controlling plate, a pivotal mounting device comprising two parallel hinge pivots, each carrying an independent hinge leaf and a common leaf between them, attaching the plate at the end of the blade, so constructed and arranged that the plate may be selectively located at 65 90° to the front of the blade, in approximate alignment with the blade, or at 180° from that position and on the back of the blade, selectively lockable means rigidly confining the plate and blade in each of said first two mentioned positions, and means selectively positioning the plate in the arc of a circle 70 about a point on the pivotal mounting device.

75 15. In mechanism of the class described, a cutting blade, a dirt controlling plate, a pivotal mounting device comprising two parallel hinge pivots, each carrying an independent hinge leaf and a common leaf between them, attaching the plate at the end of the blade, so constructed and arranged that the plate may be selectively located at 80 90° to the front of the blade, in approximate alignment with the blade, or at 180° from that position and on the back of the blade, 85 selectively lockable means rigidly confining the plate and blade in each of said first two mentioned positions, and means selectively positioning the plate in the arc of a circle 90 about a point on the pivotal mounting device.

95 16. In mechanism of the class described, a cutting blade, a dirt controlling plate, a pivotal mounting device comprising two parallel hinge pivots each carrying an independent hinge leaf and a common leaf be-

100 tween them, attaching the plate at the end of the blade, so constructed and arranged that the plate may be selectively located at 90° to the front of the blade, in approximate alignment with the blade, or at 180° from that position and on the back of the blade, means selectively positioning the entire pivotal mounting across the blade lengthwise of its cutting end, and means selectively positioning the plate in the arc of a circle about 105 a point on the pivotal mounting device.

110 17. In mechanism of the class described, a cutting blade, a dirt controlling plate, a pivotal mounting device comprising two parallel hinge pivots each carrying an independent hinge leaf and a common leaf between them, attaching the plate at the end of the blade, so constructed and arranged that the plate may be selectively located at 115 90° to the front of the blade, in approximate alignment with the blade, or at 180° from that position and on the back of the blade, selectively lockable means rigidly confining the plate and blade in each of said first two mentioned positions, means selectively positioning the entire pivotal mounting across the blade lengthwise of its cutting end, and means selectively positioning the plate in the arc of a circle about a point on the pivotal mounting device.

120 18. In mechanism of the class described, two hinges each including two leaves and an intervening pivot, means detachably securing one leaf of each hinge together to make a common leaf, and means adjusting 125

the connecting leaves so that one hinge pivot is moved axially parallel to the other hinge pivot.

18. In mechanism of the class described two hinges each including two leaves and an intervening pivot, means detachably securing one leaf of each hinge together to make a common leaf, means adjusting the connecting leaves so that one hinge pivot is moved axially parallel to the other hinge pivot and a quadrant device for detachably securing the common leaf in different angular positions with reference to the other leaf of one of the hinges.
19. In mechanism of the class described two hinges each including two leaves and an intervening pivot, means detachably securing one leaf of each hinge together to make a common leaf, means adjusting the connecting leaves so that one hinge pivot is moved axially parallel to the other hinge pivot, a quadrant device for detachably securing the common leaf in different angular positions with reference to the other leaf of one of the hinges, a plate, means for detachably securing the plate to the last mentioned leaf and means for securing the free leaf of the other hinge to a fixed support for the purposes set forth.
20. In mechanism of the class described, two hinges each including two leaves and an intervening pivot, means detachably securing one leaf of each hinge together to make a common leaf, and a quadrant device for detachably securing the common leaf in different angular positions with reference to the other leaf of one of the hinges.
21. In mechanism of the class described, a plate support comprising two parallel hinge pivots each carrying an independent hinge leaf and a common leaf between them, means securing one independent leaf to a

fixed support, means for securing a plate to the other independent leaf and latch mechanism on the hinge pivot nearest the last leaf 45 for engaging a fixed support.

22. In mechanism of the class described, a cutting blade, a dirt controlling plate, a pivotal mounting device attaching the plate at the end of the blade so constructed that 50 the plate may be selectively located in substantial alignment with the blade and in different angular positions in reference thereto, and means in the pivotal mounting mechanism for locking the plate in predetermined 55 position with reference to the blade.

23. In mechanism of the class described, a cutting blade, a dirt controlling plate, a pivotal mounting device attaching the plate at the end of the blade so constructed that the 60 plate may be selectively located in substantial alignment with the blade and in different angular positions in reference thereto, means locking the plate in predetermined position with reference to the blade, and an 65 adjustable mounting for the blade, on the pivotal mechanism, by which the blade may be tilted in the arc of a circle about a point on the pivotal mounting.

24. In mechanism of the class described, a 70 cutting blade, a dirt controlling plate, a pivotal mounting device attaching the plate at the end of the blade so constructed that the plate may be selectively located in substantial alignment with the blade and in different 75 angular positions in reference thereto, means locking the plate in predetermined position with reference to the blade, and means selectively positioning the entire pivotal mounting across the blade length- 80 wise of its cutting end.

In witness whereof, I have hereunto subscribed my name.

WILLIAM T. BEATTY.
